UNITED STATES PATENT OFFICE.

WILLIAM B. C. HERSHHEY, OF COLUMBUS, OHIO.

DESIGN FOR A VEHICLE-SEAT HANDHOLD.

SPECIFICATION forming part of Design No. 34,867, dated July 30, 1901.

Application filed July 21, 1900. Serial No. 24,451. Term of patent 3½ years.

To all whom it may concern:

Be it known that I, WILLIAM B. C. HERSHHEY, a citizen of the United States, residing at Columbus, in the county of Franklin and State 5 of Ohio, have invented and produced a new and original Design for Vehicle-Seat Handholds, of which the following is a specification, reference being had to the accompanying drawings, forming part thereof.

10 Figure 1 is a view in perspective of my newly-designed handhold, and Fig. 2 is a view in elevation of the same.

Similar letters refer to similar parts throughout both views.

15 As shown in the drawings, the leading or material feature of my design consists in the double-ogee form of handhold *a*, these bends comprising, first, the forward and thence in-

ward or rearward compound curve, which bends are more clearly shown at *b b* in Fig. 2, 20 and, second, the outward and thence inward curves *c c*, which are more clearly shown in Fig. 1. As illustrated in the drawings, the upper and inner ends of the handholds lead outward from angular attaching-heads *d*, 25 while the lower end thereof meets the outer end of a laterally-projecting horizontal foot *e*.

Having described my invention, what I claim as new, and desire to secure by Letters Patent, is—

30 The design for a vehicle-seat handhold as herein shown and described.

WILLIAM B. C. HERSHHEY.

In presence of—

P. S. KARSHNER,

A. L. PHELPS.
